UNITED STATES PATENT OFFICE

SAMUEL J. BOYD, OF LOS ANGELES, CALIFORNIA

ROTARY DRIVE TRIP HAMMER

Application filed January 11, 1928. Serial No. 246,074.

My invention is a rotary drive trip hammer.

An object of my invention is the construction of a trip hammer which, by means of a rotary drive, is raised or pressed back against the resistance of a driving spring and on each turn of the rotary drive device the hammer is released, being driven against an anvil or the device to be operated on, such as a tool.

10 A further object of my invention is a trip hammer having a rotary drive device which may be connected to a rotary chuck of any type of power mechanism, such as a rotary drill, and such drill has an arm with a roller 15 mounted thereon which engages a partial screw-shaped cam. This cam lifts or presses back the hammer against the resistance of the compression spring and, on a part rotation, releases the hammer to allow it to drop or be 20 forced against the tool. The mechanism is arranged so that as the arm continues its revolution, it will again engage the cam and thus force the hammer back into position for the power stroke.

25 A further object of my invention is the construction of a rotary drive trip hammer of a simple construction in which the hammer may be supported in one hand, the driving tool, if necessary, being supported by the other hand, 30 and the hammer being reciprocatingly mounted in a casing or holder and guided in a straight reciprocating motion, there being a compression spring to give the power stroke. The power drive is through the cap or cover 35 of the casing and a rotary shaft mounted therein is connected in a manner to allow simple assembling of the device and disassembling for repairs, or the like.

My invention is illustrated in the accompanying drawings, in which:

Figure 1 is a vertical section taken substantially on the line 1—1 of Fig. 3 in the direction of the arrows.

Fig. 2 is a bottom view taken in the direction of the arrow 2 of Fig. 1.

Fig. 3 is a horizontal section on the line 3—3 of Fig. 1 in the direction of the arrows.

Fig. 4 is a vertical section through the hammer taken substantially on the line 4—4 of 50 Fig. 3.

In constructing my invention I utilize a casing or housing 11 which has a lower section 12 with preferably cylindrical walls 13 and a horizontal base 14. This base has a neck 15 extending downwardly therefrom, such neck 55 being shown as having an angular passage 16 therein, this being shown as hexagonal; such passage is adapted to form a mounting for a tool, indicated dotted by the numeral 17. The base has a bore 18 for the projection of 60 part of the hammer, as described hereunder, this being concentric to the passage 16. A handle 19 is secured to one side of the lower section 12. This section also has an annular recess 20 with a flat ring 21 secured to the 65 base above such recess by screws 22, the recess forming a space for packing or the like. There are also guide studs 23 threaded through the walls, said studs having guide ends 24 for a purpose hereunder set forth. 70 There is a fiber washer 25 fitted in the base at the angle of the base with the side walls 13.

The hammer, designated generally by the numeral 30, has preferably a cylindrical body portion 31 with vertical grooves 32 therein, 75 these grooves engaging the guide ends 24 of the studs 23. There is a projecting hammer end 33 which extends through the bore 18 and is adapted to give the hammer stroke on the tool 17. The hammer has a large cored-out section 34 which has a cam 35 formed on one side. This cam at one end has a thin section 36 and at the other end a thick section 37, whereby the surface 38 conforms to a helical thread to allow lifting of the hammer as 80 hereunder set forth. At the base of the hammer there is an annular shallow recess 39 with air ducts 40 connecting therethrough from the top of the hammer. An annular ledge 41 forms the seat for a compression spring 42 85 which bears on this seat and on the cap or cover, as hereunder set forth, there being a spacing shoulder 42' centering the lower end of the spring. The hammer is provided with a plurality of sockets 43 in which are fitted 90 compression springs 44, these springs bearing on the base to lessen the jar of the lower annular edge 45 of the hammer on the washer 25. The upper part of the hammer has preferably an exterior cylindrical surface 46. 100

The cover 50 is formed with a downwardly extending flange 51 which is illustrated as having a screw-threaded connection with the walls 13 of the lower section of the casing, 5 and this cover has a ring like fin 52 which fits over the outside section 46 of the hammer with a clearance, such fin functioning to center the top of the spring 42 in its bearing against the under side of the cover. There 10 is a bearing section 53 with a bore there-through extending downwardly through the cover and above this there is a larger bore 54 having an annular ledge 55 for a purpose hereunder set forth.

15 The drive comprises a spindle 60 which is attached to be engaged by a chuck illustrated dotted at 61. This spindle has an annular shoulder 62 fitting in the large bore 54 and mounted on antifriction bearings 63, the 20 lower bearing fitting on the ledge 55 and the upper bearing on the lower face of the shoulder 62. A gland 63 is bolted to the cover and has a packing 64 therein. The lower end 65 of the spindle has a screw-threaded socket 25 66 which engages the upper screw threaded end of the rotary shaft 67; this shaft has a lateral arm 68 at the bottom with a journal stud 69 fitting therein. This stud has a screw-threaded section 70, a cylindrical section 71 30 and a head 72. The cylindrical section forms a mounting for the roller 73.

The manner of operation and functioning of the hammer is substantially as follows: As will be seen from Fig. 3, the cam 35 only occupies substantially half of the bore 34 so that the arm 68 may be inserted downwardly into the lower part of this bore, a roller passing in the portion unobstructed by the cam. When the spindle 60 is rotated by any suitable chuck 61, such as the chuck of an electric drill, the arm 68 carrying the roller 73 is rotated. This roller engages first underneath the end 36 of the cam 35 and follows the cam surface 38 to the thick section 37.

45 On the rotation of the roller, the hammer is lifted on account of the roller running on the cam surface 38 and such action compresses the spring 42. As this cam, as above mentioned, is only substantially half a circle 50 in length, when the roller passes off the end of the cam surface at the thick section 37, the compression spring 42 forces the hammer downwardly.

This downward power stroke causes the 55 hammer end 33 to strike the tool 17 held in the passage 16. Should the device be operating idle, that is, without the hammer end striking the tool, the springs 44 take up a certain amount of the jar of the hammer and 60 prevent the fiber washer 25 from being hammered to pieces. The air ducts 40 allow free passage of air from the annular shallow recess 39 to the top of the hammer and the reverse on the up and down reciprocating strokes of the hammer. After the hammer

undergoes its power stroke, as the roller continues its rotation, it again catches on to the shallow part 36 of the cam and again grips the hammer against the compression of the spring 42, this action being continuous and 70 operating in continuous cycles.

It will be noted that by my construction the cam 35 is in the form of a partial shelf-like structure on the interior of the hollow hammer and that this cam structure only extends partly around the inside circumference of this hollow hammer. Such an arrangement allows the roller to be inserted downwardly through the open part and to engage underneath the thin part of the cam, such as 80 illustrated at 36 in Fig. 4.

Such construction also allows a certain amount of rebound without danger of the roller coming in contact with the cam as at the time of the rebound the roller is traveling 85 through the open space in the shelf-like cam.

Various changes may be made in the principles of my invention without departing from the spirit thereof, as set forth in the description, drawings and claims.

I claim:

1. A trip hammer comprising in combination a casing having a passage at one side for insertion of tools, a hammer having lateral grooves with studs in the casing engaging said grooves and having a hammer end to strike the tools in said passage, said hammer having a cored-out section with a helically curved cam extending partly thereabouts, a cover having an inwardly extending journal section with a rotary shaft mounted therein, a compression spring between the hammer and the cover, an arm secured to said shaft and having a roller, the roller engaging the said cam, and reacting springs between the hammer and the casing, and a spindle connected to the shaft, extending outwardly beyond the cover and adapted to directly engage a driving device, the hammer having an annular shallow recess in the base with a lower annular edge, the casing 100 having a washer to engage said edge.

2. A trip hammer comprising in combination a casing having a passage at one side for insertion of tools, a hammer having lateral grooves with studs in the casing engaging said 115 grooves and having a hammer end to strike the tools in said passage, said hammer having a cored-out section with a helically curved cam extending partly thereabouts, a cover having an inwardly extending journal section with a rotary shaft mounted therein, a compression spring between the hammer and the cover, an arm secured to said shaft and having a roller, the roller engaging the 120 said cam, and reacting springs between the hammer and the casing, and a spindle connected to the shaft, extending outwardly beyond the cover and adapted to directly engage a driving device, the hammer having an annular shallow recess in the base with a 125 130

lower annular edge, the casing having a washer to engage said edge, there being a plurality of air ducts through the hammer from the said annular recess to the top of the hammer.

5 3. A trip hammer comprising in combination a supporting structure having a reciprocatingly mounted hammer with a central cored-out section, a shelf-like structure extending partly around the inner circumference of the cored-out section and having a cam surface underneath, a rotary lifting element rotating at right angles to the reciprocation of the hammer and insertable through 10 the open section of the shelf, said lifting element engaging the cam and elevating the hammer and allowing the hammer to drop on disengaging the cam.

15 4. A trip hammer comprising in combination a supporting structure having a reciprocating hammer mounted therein, said hammer having a cored-out section with a shelf-like structure extending partly around its inner circumference, a cam surface formed 20 on the underside of said shelf-like structure, said cam having a helical curve, a rotary shaft having a roller extending from one side thereof, the shaft rotating in a plane at right angles to the reciprocation of the hammer, the roller being insertable under the shelf through the open space therein and 25 engaging the cam, thereby lifting and releasing the hammer.

30 5. A trip hammer comprising in combination a casing having a cover thereon and an opening in the bottom for a part of a reciprocating hammer mounted in the casing, said hammer having a cored-out section with a shelf extending partially around its inner 35 circumference, said shelf having a cam on its under surface, the cover having a rotary shaft journaled therein and extending therethrough with a roller on one side of the shaft insertable through the open section of 40 the shelf and engaging the cam on the underside of the shelf.

45 6. A trip hammer comprising in combination a tubular casing having an opening in the base for part of a hammer reciprocal 50 therein, said hammer having a cored-out section with a shelf extending partially around its inner circumference, said shelf having a cam surface underneath, a cover mounted on the casing and having a depending bearing 55 section with a large bore at the top and a smaller bore at the bottom, and an intervening ledge, a shaft having a thrust bearing on said ledge and a bearing in said bearing section, a roller extending from one side 60 of the shaft at the bottom, insertable in the cored-out section through the opening in the shelf and engaging a cam, whereby the rotation of the shaft lifts and allows dropping of the said hammer.

65 7. A trip hammer comprising in combina-

tion a hollow casing having a cover at the top, said cover having a depending central bearing section with an upper large bore and a smaller lower bore with an intervening ledge, a spindle having a shoulder journaled in the 70 large bore, a lower extension of the spindle having a bearing in the bearing section and having a socket with a rotary shaft engaged therein, said shaft having a roller on one side thereof, said roller engaging a cam on a reciprocating hammer, slidably but not rotatably movable in the casing, the rotation of the shaft causing the roller to lift and to release said hammer, and means to force the hammer in a direction opposite to its lift. 75

80 8. A trip hammer as claimed in claim 7, the hammer having a hollow interior with a shelf extending partially around its inner surface, said shelf having a cam surface underneath, engaged by the roller, the roller being insertable through the openings in the shelf.

In testimony whereof I have signed my name to this specification.
